(57) **CLAIM**

The ornamental design for a tape line wiper, as shown and described.

DESCRIPTION

FIG. 1 is a side elevational view of the tape line wiper showing my new design, as mounted on a tape being wiped, the latter being shown in broken lines for purposes of illustration and do not form part of the claimed design;
FIG. 2 is a top plan view of my tape line wiper;
FIG. 3 is a right side elevational view thereof, with a left side elevational view being a mirror image thereof;
FIG. 4 is a bottom plan view thereof;
FIG. 5 is a front elevational view thereof; and,
FIG. 6 is a rear elevational view thereof.

The broken lines represent environment and form no part of the claim. The boundary lines represent boundaries of the claim and form no part of the claim.
